UNITED STATES PATENT OFFICE.

CHARLES J. DE LA FONTAINE, OF DALLAS, TEXAS, ASSIGNOR TO TRINITY FOLDING BOOTH COMPANY, OF ST. LOUIS, MISSOURI, A CORPORATION OF MISSOURI.

FOLDING BOOTH.

1,407,260.

Specification of Letters Patent. Patented Feb. 21, 1922.

Application filed January 8, 1921. Serial No. 435,880.

To all whom it may concern:

Be it known that I, CHARLES J. DE LA FONTAINE, a citizen of Switzerland, residing at Dallas, in the county of Dallas and 5 State of Texas, have invented certain new and useful Improvements in Folding Booths, of which the following is a specification.

This invention relates to new and useful 10 improvements in folding booths.

The object of the invention is to provide a booth such as is used for demonstrating foods and merchandise, which booth may be folded into a compact form for transportation, and which may be readily unfolded and placed in position without the services of a skilled mechanic. A further object is to provide a booth structure which will be self sustaining when erected and which will 15 not require the use of nails, screws or other additional fastenings when being unfolded and placed in position for service. One of the particular features of the invention is the provision of ample space for displaying advertising matter and literature and otherwise ornamenting the booth, whereby it will be of an attractive and pleasing appearance. A very important object is to arrange and correlate the parts so that the booth may be 20 expeditiously folded and unfolded and easily handled without the exercise of undue strength.

A construction designed to carry out the invention will be hereinafter described together with other features of the invention. 25

The invention will be more readily understood from a reading of the following specification and by reference to the accompanying drawings, in which an example of the 30 invention is shown, and wherein:

Fig. 1 is a front elevation of a booth constructed in accordance with my invention, and unfolded in position for use,

Fig. 2 is a vertical sectional view on the 35 line 2—2 of Fig. 1,

Fig. 3 is a cross-sectional view on the line 3—3 of Fig. 1,

Fig. 4 is an enlarged cross-sectional detail on the line 4—4 of Fig. 1,

50 Fig. 5 is a plan view showing the booth folded, and

Fig. 6 is a cross-sectional view on the line 6—6 of Fig. 5.

In the drawings the numeral 10 designates 55 a lower front panel and 10' an upper front

panel. The lower front panel is composed of upright corner strips 11 connected at their bottom by a cross rail 12. A top cross rail 13 extends between the strips at the top of the panel. A center mullion 14 connects 60 the rails 12 and 13. The panel is covered with combination board such as card board or the like.

The strips 11 extend above the top of the panel 10 and are joined to the lower end of 65 upper strips 11' by hinges 15 placed on the front of said strips. The upper ends of the strips 11' are connected by a cross rail 16, above which a pair of inclined supports 17 are provided. The upper panel 10' is terminated some distance above the hinges 15 and is preferably arched as is shown in the drawing, at both its bottom and top, the latter being braced by the supports 17. This panel is formed of the same material as the 70 panel 10.

Lower wings or side panels 18 are provided at each side of the front panel 10 and upper wing or side panels 18' are provided at each side of the panel 10'. Each lower 80 panel 18 has an upright front strip 19 and an upright rear strip 20 each terminating at the same height as the strips 11. The strips 19 and 20 are connected at their bottom by cross rails 21 and at the top of each 85 panel by a cross rail 22 which is in substantially the same horizontal plane as the cross rail 13. The upper panels 18' each have a front strip 19' and a rear strip 20' registering with the strips 19 and 20 respectively. 90 The upper ends of the strips 19' and 20 are connected by cross rails 23. The panels 18' are likewise arched so as to harmonize with the front panel 10' and each includes a sheet of composition board, which is also 95 used for the lower panels 18.

The strips 19 and 19' are hinged to the strips 11 and 11' respectively by hinges 24. Hooks 25 provided on the lower ends of the strips 20' engage eyes 26 on the upper ends 100 of the strips 20, thus preventing the front panels from falling forward. The side panels are disposed at substantially right angles to the front panels and open spaces are provided between the upper and lower panels 105 at the front and sides of the booth. These spaces are at such an elevation as to give any person within the booth an unobstructed view and a free circulation of air to the booth. The composition panels permit of the easy 110

attaching of advertising posters and literature or other ornamentation and decorations, which may also be applied to the inside of the upper side panels 18' if desired. The strips 5 11, 11' and, 19 and 19' form corner posts and being at right angles give rigidity to the booth. The hinges 15 may be concealed by wrapping decorating material around the corner posts or otherwise covering the same.

10 I provide a counter form of front sections 27 hinged together at the center of the booth and side sections 28, the sections having their adjoining ends mitered so as to fit. The front sections 27 have dowel pins 29 entering sockets 30 in the side sections 28. The side sections 28 have notches 31 at their rear ends receiving the strip 20 and notches 32 at their front mitered end receiving the strips 19; while the sections 27 have notches 33 at their 15 mitered end receiving the front strip 11. The counter sections rest upon the top cross rails 13 and 22 and overhang the inner and outer sides of the lower panels. The inner corners of the side counter sections may be rounded 20 to obviate sharp corners. Cross bars 34 are mounted between the strips 19 and 20 of each side panel and support a shelf 35 which has its end suitably notched as is best shown in Fig. 4, so as to rest on the cross bars below 25 the counter to form a table to be used by the person occupying the booth.

It will be seen that the strips, cross rails, support, counter sections and the shelf may be constructed of wood and this together with 30 the composition sheets, which as before stated may be heavy cardboard, make for a very light and easily handled structure. The booth when erected or unfolded may be easily moved if desired, and yet is sufficiently substantial to sustain itself when in use. When 35 it is desired to fold the booth the shelf 35 and the counter sections 27 and 28 are removed. It will be noted that the counter sections serve to hold the sides of the booth in fixed 40 relation to the front and prevent the booth from collapsing or spreading when in use. After these parts have been removed the hooks 25 may be disengaged from the eyes 26 and the sides of the booth swung inwardly 45 against the back of the front. The panels 18' which are folded against the upper panel 10' are preferably of such width as to meet when folded. The folded upper panels may then be swung downward upon the front 50 panel 10 and the lower side panels 18 then folded in against the rear side of the front panel 10 whereby a flat and compact structure is had. The counter sections 27 may be folded and slipped in between the upper 55 panel 10' and one of the side upper panels 18'; while the two side counter sections 28 may be slipped between the other side panels and the panel 10' as is shown in Figs. 5 and 6. The shelf 35 may be slipped in between the 60 tops of the panels 18' and the support 17,

or otherwise packed with the structure. The whole device may be suitably enclosed in a box or other package (not shown) and readily transported.

When it is desired to unfold and erect the 70 booth it is merely necessary to remove the shelf and counter sections and set the folded structure up on edge so that the front panel 10 rests upon the floor and swing the folded 75 lower side panels 18 outwardly. The folded panels 10' and 18' are then swung upwardly and the latter swung outwardly and fastened to the panels 18 by means of the hooks 25. The counter sections are then placed in position and the shelf 35 inserted. This can all 80 be done in a remarkably short time and by the average person without assistance of a skilled mechanic. No extra fastenings or supports are required.

Various changes may be made in the dimensions and construction of the booth without departing from spirit of the invention.

What I claim, is:

1. In a folding booth, a lower front panel having side panels hinged thereto, an upper 90 front panel hinged to the lower front panel and having upper side panels hinged thereto adapted to register with the side panels of the lower front panels, the upper front panel being arranged to fold downwardly against 95 the lower front panel, a removable counter mounted on the lower panels, and a removable shelf supported within the lower panels.

2. In a folding booth, a lower front panel including upright strips disposed near the 100 vertical edges thereof, an upper front panel including upright strips disposed near the vertical edges thereof and hinged to the upright strips of the lower panel so that the upper panel is adapted to fold downwardly 105 against the lower panel, lower side panels having upright strips at their front and rear vertical edges, the forward strips of the lower side panels being hinged to the strips of the lower front panel so that the lower 110 side panels are adapted to be folded upon the lower front panel, upper side panels having upright strips at their forward and rear vertical edges, the forward strips of the upper side panels being hinged to the forward strips 115 of the upper front panel so that the upper side panels may fold inwardly against the upper front panel, means for connecting the lower ends of the rear strips of the upper side panels with the upper ends of the rear strips 120 of the lower side panels, a front counter adapted for arrangement above the lower front panel to be supported thereby and having its ends mitered and provided in such mitered ends with notches to receive the 125 upright strips of the said lower front panel, side counters adapted to be arranged above the lower side panels and having their forward ends mitered, said side panels being provided in their forward and rear ends with 130

notches to receive the forward and rear strips of the lower side panels.

3. In a folding booth, a lower front panel having side panels hinged thereto, an upper 5 open front panel hinged to the lower front panel and having upper open side panels hinged thereto adapted to register with the side panels of the lower front panel, the upper front panel being arranged to fold 10 downwardly against the lower front panel, and a removable counter mounted on the lower panels within the openings of the upper front and side panels.

4. In a folding booth, upright front strips 15 hinged together at their ends so that they may be folded longitudinally upon each other, upper and lower panels carried by the strips, the upper panel being spaced from the lower panel to provide an opening, 20 upright side strips hinged to the front strips to fold transversely thereof, upper and lower side panels carried by the side strips, the upper side panels being spaced from the lower side panels to provide openings, upright 25 rear strips supporting the side panels, means for fastening the rear strips together near their inner ends, and said side panels being

adapted to fold inwardly against the front panel and the front panels being arranged to fold downwardly upon each other, and removable counter sections arranged upon the lower panels within the openings between the upper and lower panels. 30

5. In a folding booth, a lower front panel, an upper front panel hinged at its lower 35 end from the top of the lower front panel and adapted to swing longitudinally of the lower front panel down upon the same, said upper and lower front panels having an opening formed therein, lower side panels 40 hinged to the lower front panels and adapted to fold transversely thereof inwardly upon the same, upper side panels hinged to the upper front panel and adapted to swing inwardly upon the same, means for detachably 45 connecting the inner ends of the rear portions of the upper and lower side panels, and a counter mounted upon the lower front panel within the opening between the upper and lower front panels and being adapted to be 50 removed from such opening.

In testimony whereof I affix my signature.

CHARLES J. DE LA FONTAINE.
